ASH TRAY

Matthew E. Gerlat, Milwaukee, Wis.

Application September 25, 1950, Serial No. 12,345

Term of patent 14 years

(Cl. D85—2)

To all whom it may concern:

Be it known that I, Matthew E. Gerlat, a citizen of the United States, residing at Milwaukee, in the county of Milwaukee and State of Wisconsin, have invented a new, original, and ornamental Design for an Ash Tray, of which the following is a specification, reference being had to the accompanying drawing, forming a part thereof, and in which:

I claim:

The ornamental design for an ash tray, as shown.

MATTHEW E. GERLAT.
